(57) CLAIM

The ornamental design for a decorative plunger cover and holder, as shown and described.

DESCRIPTION

FIG. 1 is a front elevational view of the decorative plunger cover and holder of the present invention, the rear view being a mirror image thereof;

FIG. 2 is a left side elevational view of the decorative plunger cover and holder of FIG. 1, the right view being a mirror image thereof;

FIG. 3 is a top plan view of the decorative plunger cover and holder of FIG. 1; and,

FIG. 4 is a bottom plan view of the decorative plunger cover and holder of FIG. 1.

The broken lines showing of a plunger in FIG. 1 is for illustrative purposes only and form no part of the claimed design.
